UNITED STATES PATENT OFFICE

GIULIO NARDUCCI, OF SOUTH TACOMA, WASHINGTON

ROTARY BRUSH

Application filed April 30, 1928. Serial No. 274,142.

This invention relates to a new and useful device in the nature of a rotary brush especially adapted for use by barbers, tonsorial artists, hair dressers and the like, for the purpose of more readily and rapidly brushing hair.

The object of the invention is to provide a rotary brush of simple construction and arrangement of parts embodying certain new and novel features hereinafter more fully described, claimed and illustrated in the accompanying drawing.

Fig. 1 is a side elevational view of my improved rotary brush.

Fig. 2 is a top plan view thereof.

Fig. 3 is a central vertical sectional view thereof.

Fig. 4 is a transverse sectional view taken on the line 4—4 of Fig. 1.

Fig. 5 is an enlarged fragmentary side elevational view illustrating in particular a further development of the handle member as embodied in my improved device.

Fig. 6 is a front elevational view thereof.

As here embodied my improved rotary brush comprises a brush body member 10, of cylindrical construction, having secured thereto, or imbedded therein bristles 11, extended therefrom, so as to provide a cylindrical brush. The body member 10 has formed therein at its lower extremity an axial opening adapted to receive the extended element 12 of the collar 13, which is secured thereto in any desired manner. The collar 13 has

formed therein an axial opening adapted to secure the pin 14, secured thereto by the threaded member 15 mounted in the collar 13. The pin 14 is extended from the collar 13 and engages in an opening formed in the enlarged

extremity 16 of the shaft 17, and is secured thereto by the threaded member 18 mounted in the enlarged extremity of the said shaft 17. The above described construction is such as will permit the said brush to be easily and readily removed from the said shaft, for cleaning, replacement or the like.

The conventional ball bearings 19 and 20, preferably of the combination rotation and thrust type are mounted intermediately on the shaft 17, and maintained thereon by the

collars 21 and 22 secured to or pressed on the said shaft. The shaft 17 is provided with flange 23, positioned at or near the upper extremity thereof, for the purpose as herein-after set forth.

The above described construction is such as will permit the shaft 17 to be rotatively mounted on the ball bearings 19 and 20. The handle as embodied in my improved rotary brush comprises a pair of handle members 24 and 25, similar or identically shaped of substantially flat side construction, and provided with arc shape, convex or curved edges 26 and 27 respectively, and opposite edges 28 and 29, respectively formed or shaped with an irregular contour, so as to provide a suitable grip adapted to conform to the fingers of the user of my improved rotary brush.

The said handle members are removably secured together by means of the threaded members 30, and have formed therein a longitudinal opening adapted to freely receive the shaft 17, and the collars 21 and 22 and to engage or grip the ball bearings 19 and 20, as a means of rotatively supporting the shaft in the said handle members. The said opening formed in the handle members is provided with an enlarged portion adapted to receive the flange 23 of the shaft 17, so as to permit the said flange to function as a thrust support for the said shaft, co-acting with the said combination thrust ball bearings.

The engaging member 31 is slidably mounted in the opening 32 formed in the lower portions of the handle members and is provided with an extended element 33 normally held somewhat extended in the lower portion of the above mentioned longitudinal opening formed in the said handle members by means of the expansion spring 34 positioned in the opening 32, directly at the rear of the engaging member 31 and in engagement therewith. The said spring is maintained therein by the threaded member 35, threadedly mounted in the opening 32, at the rear of and in engagement with the said spring. The lower extremity of the shaft 17 has formed therein a slot 36, adapted to receive the usual tongue element of the usual fitting 37 secured

to and extended from the usual flexible shaft 38, such as is commonly used to rotate or drive appliances, such as massaging tools, dentists' drillings, hair clippers and the like, and which is operatively attached to a suitable electric motor, water motor or the like, as a means of rotating my improved rotary brush.

The above described construction is such 10 as will permit the extended element 33 of the engaging member to automatically engage in the usual co-axial groove formed in the fixture 37, for the purpose of permitting my improved rotary brush to be readily and easily attached or detached from the flexible shaft, which is highly desirable and convenient when hair clippers, a massaging tool or the like are to be used, as a means of providing interchangeability of the said appliances.

20 In Figs. 5 and 6 of the accompanying drawings, I have shown a brake lever 40 hinged at one extremity thereof, as at 41 by a pin or the like carried intermediately in the handle members in proximity to the irregular edges 28 and 29 of the said handle members, and formed or bent so as to conform to the said irregular edges, and provided with an extended free element 42 or extremity, of somewhat reduced cross section and having 25 its inner surface, serrated as at 43. The above described construction is such as will permit the brake lever to conform to the fingers of the operator of my improved device, similar to the above mentioned and described irregular edges of the said handle members, and which will also permit the serrated surface 35 of the brake lever when forced or pressed inwardly by the finger of the operator, to engage or strike the above mentioned engaged extremity 16 of the said shaft 17, as a means 40 of stopping the rotation of my improved rotary brush.

I have also shown a grip member 44, hinged at one extremity to the said pin 41, and 45 formed or bent irregular so as to conform to the irregular edges of the said handle members, so as to provide the above mentioned and described convenient finger grip. The grip member 44 is provided with an extended portion 45 or extremity, adapted to provide additional gripping surface for the fingers of an operator having a comparatively large hand. The above described construction is also such as will permit the grip member 44 to be hinged upwardly as at 44', and 50 which will permit the brake lever 40 to be hinged downwardly as at 40', when desired as a means of providing somewhat different grip for the fingers of the operator in continued or prolonged use, so as to prevent or 55 eliminate cramping and fatigue to the operator.

Having thus described my invention, what I claim as new and desire to secure by United States Letters Patent is:

1. A rotary brush, comprising a handle rotatively supporting a shaft carrying a brush, said shaft being formed with an enlarged portion disposed adjacent one end of the handle, a brake lever pivotally mounted 70 at one end intermediate the ends of the handle, and extending beyond the ends of the handle, and engageable against the said enlarged portion for producing a braking action, and a grip member pivotally mounted 75 at one end coaxially with the brake lever and capable of assuming a position superimposed on the brake lever, or in the opposite direction flush against the said handle.

2. A rotary brush, comprising a handle rotatively supporting a shaft carrying a brush, said shaft being formed with an enlarged portion disposed adjacent one end of the handle, a brake lever pivotally mounted at one end intermediate the ends of the handle, 80 and extending beyond the ends of the handle, and engageable against the said enlarged portion for producing a braking action, the portion of the brake lever engageable against the enlarged portion of the shaft being serrated, 85 and a grip member pivotally mounted at one end coaxially with the brake lever and capable of assuming a position superimposed on the brake lever, or in the opposite direction 90 flush against the said handle.

3. A rotary brush, comprising a handle rotatively supporting a shaft carrying a brush, said shaft being formed with an enlarged portion disposed adjacent one end of the handle, a brake lever pivotally mounted 100 on the handle and extending beyond one end of the handle, and engageable against the said enlarged portion, and a grip member pivotally mounted on the handle and arranged for assuming a position superimposed 105 on the brake lever, or flush against the said handle.

In testimony whereof I have affixed my signature.
